CLAIM

The ornamental design for computer loveseat, as shown and
described.

DESCRIPTION

FIG. 1 is a front view of a computer loveseat, showing my
new design;

FIG. 2 is a back view of the design of FIG. 1;

FIG. 3 is a left side view of the design of FIG. 1;

FIG. 4 is a right side view of the design of FIG. 1;

FIG. 5 is a top plan view of the design of FIG. 1; and,

FIG. 6 is a bottom view of the design of FIG. 1.

The broken line showing of legs in FIGS. 1-6 is for
illustrative purposes only and forms no part of the claimed
design.
